LEON TRAGER AND HARRY F. SEVERN, OF NEWARK, NEW JERSEY, ASSIGNORS TO WORTHINGTON PUMP AND MACHINERY CORPORATION, OF NEW YORK, N. Y., A CORPORATION OF VIRGINIA

GREASE OR LUBRICANT PUMPING APPARATUS

Application filed June 2, 1931. Serial No. 541,636.

This invention relates to grease or lubricant pumping apparatus, and an object of the invention is to provide means whereby the quantity of lubricating grease pumped 5 from a suitable container may be accurately measured.

In pumping semi-hard lubricating grease into various parts of automobiles or analogous machinery, it has heretofore been the 10 practice to rely upon the number of turns of the pump piston operating handle for determining the quantity of such lubricant pumped. This means is not positively accurate and discrepancies occur in the quantity 15 of lubricant pumped, particularly at times when the container is practically empty, often resulting in the purchaser being charged for a greater quantity of the lubricant than he receives.

20 An object of the present invention is to provide a lubricating grease pumping apparatus or unit by means of which the quantity of lubricant pumped will be accurately indicated, thereby eliminating chance or 25 guesswork in such pumping, and insuring that the purchaser receives the quantity of lubricant for which he pays.

More specifically, the present invention comprehends the provision of a measuring 30 meter on the discharge side of the pump, through which the lubricating grease passes, and which accurately registers the quantity pumped, and further provides, in combination with such an arrangement, means which 35 will prevent the operation of the meter by air pumped and especially at times when the container is practically empty and the pump sucks a quantity of air thereinto with the lubricant.

40 With these and other objects in view, as may appear from the accompanying specification, the invention consists of various features of construction and combination of parts, which will be first described in connection with the accompanying drawings, 45 showing grease of lubricant pumping apparatus of the preferred form embodying the invention, and the features forming the invention will be specifically pointed out in the 50 claims.

In the drawings:

Fig. 1 is a side elevation of the improved pumping apparatus.

Fig. 2 is a top plan of the improved pumping apparatus.

Fig. 3 is a fragmentary section through the improved grease pumping apparatus.

Fig. 4 is a side elevation of a modified form of the pumping apparatus.

Fig. 5 is a fragmentary section through the modified form of the apparatus.

Referring more particularly to the drawings, a container 1 is used for containing the lubricating grease such as is used in differentials, transmissions, etc., about automobiles or 60 analogous machinery, and a pump 2 of any approved construction is attached to the container 1 and has its suction pipe 3 depending into the container. In the drawings the pump piston 4 is reciprocated in the suction 70 pipe 3 through the medium of any approved type of mechanism, by rotation of the handle 5. The structure just described is the approved type of dispenser for lubricating grease now commonly in use. In the present-day dispensing apparatus, the grease pumped is discharged through a suitable 75 hose 6. The capacity of the pump being known, it has heretofore been the practice to determine the quantity of lubricating grease 80 discharged, by the number of turns of the handle 5; this, however, is not very accurate because many things cause variations in the quantity of grease pumped on each turn of the handle, such as, for instance, when the 85 level of the grease in the container 1 reaches the lower end of the suction pipe 3 and the pump draws or sucks air with slugs of the grease, slippage of the parts or the failure of the operator to make a complete turn or revolution of the handle.

The present invention comprises means for accurately and positively measuring the quantity of lubricating grease delivered by the apparatus, and comprises a meter 10 of 95 any approved construction which is connected to the discharge pipe 11 of the pump 2 and to the outlet of which meter the hose 6 is connected, so that all grease pumped must pass through the meter 10 and be registered there- 100

by before it is delivered. The delivered quantity of grease is accurately registered on the dial 12 of the meter. However, owing to its construction, meters of this type will 5 operate on air as well as on the lubricating grease, so that at times when the quantity of grease in the container 1 is low and the pump is sucking air, such air passing through the meter would be registered. To overcome the 10 registering of air by the meter a bypass 15 is provided which is connected in the discharge line of the pump between the pump 2 and the meter 10. The pipe 15 extends into the container 1 and while it is shown in the drawings 15 of small diameter, it is understood that it may be made of any size desirable and may be connected at any convenient point between the meter and the supply of grease in the container 1, to permit the escape of air from the 20 discharge line of the pump prior to its entrance to the meter 10. The discharge of air through the bypass 15 will be permitted because a resistance is set up in the meter greater than the resistance through the bypass 25 15, owing to the construction of the meter and the air will, therefore, pass out through the bypass and not be recorded or measured. Any lubricating grease which might also pass through the bypass 15 will 30 be returned to the container 1.

In the modified form of the invention shown in Figures 4 and 5 of the drawings, an additional resistance is provided between the bypass 15' and the meter 10', this additional resistance being in the form of a spring loaded check valve 20 of any approved form. As noted in the drawings, the check valve is placed between the inlet 21 to the meter 10' and the bypass 15', and it may be found desirable to use such additional resistance in instances where relatively thin lubricating grease is being pumped. The check valve merely acts in conjunction with the meter to provide resistance and insure the air passing 45 through the bypass 15' and prevent its entrance into and passage through the meter. In all other respects the modified form of the invention is similar to the preferred form previously described.

50 While the bypasses 15 and 15' are shown as extending into the container 1 to a depth in close proximity to the lower end of the pump suction pipe 3, it is to be understood that they may terminate at or close to the top of the container or may open out exteriorly of the container 1, if it is so desired, without departing from the spirit of the present invention.

From the foregoing description, taken in 60 connection with the accompanying drawings, it will be apparent that the quantity of lubricating grease discharged will be accurately measured, and errors in the computing of the quantity pumped will be eliminated.

65 It will be understood that the invention is

not to be limited to the specific construction or arrangement of parts shown, but that they may be widely modified within the invention defined by the claims.

What is claimed is:

70 1. In a grease pumping apparatus, the combination, with a container and a pump mounted thereon for pumping lubricant from the container, of a measuring meter in the discharge line of the pump, and an air escape in the discharge line of the pump between the pump and meter to permit escape of air pumped prior to its entrance into the meter.

75 2. In a grease pumping apparatus, the combination, with a container and a pump mounted thereon for pumping lubricant from the container, of a measuring meter in the discharge line of the pump, and a bypass pipe connected to the pump discharge between the pump and meter to permit escape of air pumped prior to its entrance into the meter.

80 3. In a grease pumping apparatus, the combination, with a container and a pump mounted thereon for pumping lubricant from the container, of a measuring meter in the discharge line of the pump, and a bypass pipe connected to the pump discharge between the pump and meter to permit escape of air pumped prior to its entrance into the meter, said bypass pipe projecting into said container.

85 4. In a grease pumping apparatus, the combination, with a container and a pump mounted thereon for pumping lubricant from the container, of a measuring meter in the discharge line of the pump, an air escape in the discharge line of the pump between the pump and meter to permit escape of air pumped prior to its entrance into the meter, and a check valve between the meter and pump in the discharge line of the pump.

90 5. In a grease pumping apparatus, the combination, with a container and a pump mounted thereon for pumping lubricant from the container, of a measuring meter in the discharge line of the pump, a bypass pipe connected to the pump discharge between the pump and meter to permit escape of air pumped prior to its entrance into the meter, and a spring loaded check valve in the discharge line of the pump between the pump and meter.

95 In testimony whereof we affix our signatures.
